WALL PAPER REMOVER

John P. Howard, Cleveland, Ohio

Application April 24, 1952, Serial No. 284,074

7 Claims. (Cl. 126—271.1)

This invention relates to improvements in wall paper removers.

One of the objects of the present invention is to provide a wall paper remover having means for generating steam or other hot vapor close to the surface of the wall paper to be removed.

A further object of the present invention is to provide a wall paper remover having a moisture applicator movable between an operative position in contact with a heating means for generating steam for removing the wall paper and an inoperative, normal position spaced from the heating means wherein no steam is generated.

A further object of the present invention is to provide a wall paper remover having a moisture applicator movable between an operative position in contact with a heating means for generating steam for removing wall paper and an inoperative, normal position spaced from the heating means wherein no steam is generated, and having a moistening means for engaging the applicator in its inoperative position with a controlled wetting to dampen only the applicator but not the heating means spaced therefrom.

A further object of the present invention is to provide a wall paper remover light in weight, easy to use and inexpensive to manufacture.

Other features of this invention reside in the arrangement and design of the parts for carrying out their appropriate functions.

Other objects and advantages of this invention will be apparent from the accompanying drawings and descriptions and the essential features will be set forth in the appended claims.

In the drawings,

Fig. 1 is a side elevational view of the wall paper remover with portions thereof cut away and shown in section and with the applicator and heating means spaced apart in their normal or inoperative position;

Fig. 1a is a partial view of the post in Fig. 1 but with a steam deflector added thereto;

Fig. 2 is an end elevational view of the wall paper remover of Fig. 1 with portions again cut away and shown in section;

Fig. 3 is a top plan view of the wall paper remover of Fig. 1;

Fig. 4 is a top plan view of the moistening means with a portion of the sponge and the inwardly directed flanges cut away to more clearly show the structure of the pan;

Fig. 5 is a longitudinal sectional view through the wall paper remover wherein it is shown in its operative or wall paper removing position;

Fig. 6 is a longitudinal sectional view of a modified form of wall paper remover wherein the applicator and heating means are in their normal or inoperative position;

Fig. 7 is an enlarged view of the right hand portion of Fig. 6;

Fig. 7a is a partial view of a corner of the cloth carrier in Fig. 7 but with a modified form of toweling or

2

cloth and a modified form of securement therebetween;

Fig. 8 is a perspective view of a portion of a wall paper remover shown in Fig. 6;

Fig. 9 is another modified form of wall paper remover with the applicator and heating means in their normal, spaced apart, inoperative position with the applicator engaging the moistening means for controlled wetting;

Fig. 10 is a top view of the wall paper remover shown in Fig. 9;

Fig. 11 is an end view of the applicator and heating means of Fig. 9 wherein a portion is broken away and shown in section; while

Fig. 12 is a side elevational view of the wall paper remover with the heating means and the moisture applicator in their operative or wall paper removing position.

Before the wall paper remover here illustrated is specifically described it is to be understood that the invention here involved is not limited to the structural details for arrangement of parts here shown since wall paper removers embodying the present invention may take various forms. It also is to be understood that the phraseology or terminology herein employed is for purposes of description and not of limitation since the scope of the present invention is denoted by the appended claims.

The conventional method of removing wall paper by steam has many disadvantages. The apparatus generally includes a steam boiler, a large bulky unit, having a flexible conduit connected with a nozzle for directing the emerging steam against the wall paper to be removed. The disadvantages are many. The apparatus is expensive. There is always the danger that the steam boiler will blow up if the steam pressure should accidentally become too high. Generally, a gas or kerosene burner is used for heating the boiler and there is always the danger of explosion. More heat must be provided by the boiler if the steam is not to cool too much; this increases the danger of the boiler blowing up. In order to leave the combustion products of the burner out of the room, the user may need to open the windows. On a cold day, this will also cool the steam travelling through the conduit from the boiler to the nozzle. In other words, the quality of the steam impinged against the wall paper will depend upon the climate, season of the year and many other factors.

Also, the steam boiler generates a large amount of steam, much of which does not penetrate into the wall paper but escapes at the nozzle or through leaks in the boiler or conduit. The large amount of steam in the room makes it disagreeable to work on hot humid summer days and may also tend to spoil the woodwork.

The novel wall paper remover disclosed in the present application overcomes the difficulties heretofore encountered, as listed above.

The wall paper remover shown in Figs. 1 to 5 inclusive of the drawings includes a heating means which is here shown as an electrically heated plate 21 having electrical heating elements therein and closely resembling a flatiron. A thermostatic control can be provided, if desired, to make the heating responsive to the temperature of the plate. Also, the back or top of the plate in Fig. 1 may be insulated to prevent the heat from radiating upwardly to irritate the user. A handle 22 is secured to the top edge of the plate 21 by posts 23, 23. At least one of said posts is tubular in form for carrying the electrical heating wires from the flexible cord 24, connected to a source of electricity, to the heating elements of the plate 21. However, the wires need not pass through the posts if this construction is not desired.

A moisture applicator is provided. This is shown in the present disclosure as a moisture absorbing and retaining cloth 25 adapted to be moistened with a liquid and then inserted, as seen in Fig. 5 between the wall paper 26

to be removed and the heating means 21. When they are brought into contact with each other or within close proximity of each other, the heating means 21 will vaporize moisture and the vapor in turn will be driven through the wall paper to soften the adhering glue. Generally, the moisture takes the form of water and steam is generated by the heating means, but it should be understood that any other type of liquid glue solvent or softener, which can be vaporized by heat, may be used.

This invention also contemplates that the cloth 25 may be woven around and on both sides of a wire screen. This wire screen would not only reinforce the cloth but also serve as a heat conductor between the heating means and the moisture since the metallic wire screen would provide a heating surface in the cloth in intimate contact with the moisture.

Any type high absorbent cloth can be used. A good example is conventional toweling.

A carrier means, generally shown at 30, is provided for supporting the cloth or applicator 25 in association with the heating means 21. This carrier means includes a back or upper wall 31 having downwardly (Fig. 1) or forwardly (Fig. 5) directed side walls or flanges 32. In Fig. 1, these flanges each have an upwardly bent distal edge 33 having a serrated upper edge 33a thereon. When the cloth 25 is stretched over the lower edges of the downwardly directed side walls 32 and is bent over the serrated edges in the manner shown in Fig. 1, the carrier means serves as a frame for supporting the cloth in taut condition with the serrated edges serving as a means for detachably connecting the cloth to the carrier member. This invention contemplates that other equivalent types of detachable connections may be used in addition to the specific type shown as serrated edges in the present disclosure. The serrated edges are shown for convenience and not for limitation. The frame formed by the carrier means stretches the cloth along its width and length dimension to secure its taut mounting on the frame.

The carrier member, including the side walls 32, serves to localize and concentrate the steam (Fig. 5) to drive it through the wall paper to loosen or soften the glue. The steam cannot readily escape into the room.

The carrier means 30 is provided with spaced apertures 31a, 31a in the back wall 31 through which the posts 23, 23 of the handle 22 may project. Then, the carrier means 30 can freely move relative to the heating means 21 to assume either the inoperative, spaced relationship of Fig. 1 or the operative, wall paper removing relationship in Fig. 5.

The upper surface of back wall 31 in Fig. 2 may be provided with a rough and shiny surface so that any heating of the carrier means will not radiate back to annoy the user when he grips the handle 22. Also, a baffle or deflector plate 23a can be secured to each post 23 above each aperture 31a to protect the user's hand on handle 22 from any escaping steam, as shown in Fig. 1a.

Means are provided for securing the carrier means 30 and the heating means 21 together for permitting relative movement between them. This means takes the form of a resilient means normally biasing the carrier means 30 and the heating means 21 into their inoperative position shown in Figs. 1 and 2. A post 40 in Fig. 2 is secured to the heating means 21 and is spaced outwardly from but in alignment with each post 23. Each of the two posts has a threaded upper end and extends upwardly through an aligned hole in the back wall 31. A compression spring 42 surrounds each post and a nut 41 is screwed onto the threaded upper end with a washer located between the lower face of the nut and the upper end of the spring. These springs normally bias the heating means 21 and the moisture applicator 25 into spaced relationship, as shown in Figs. 1 and 2. Although two springs 42 are shown in the present disclosure to provide a sturdy construction, a lesser or greater number of springs may be used if desired.

It is apparent that the heating means 21 and the moisture applicator cloth 25 are held close together by this structure and are arranged for relative movement so that they may assume either the position in Fig. 1 or the position in Fig. 5. In Fig. 1, the heating means 21 and the moisture applicator 25 do not contact or do not lie in close proximity to each other. This is their normal, inoperative position into which they are urged by the springs 42. The applicator is spaced from the heating means so that no steam is generated from the moisture in the applicator while the wall paper remover is not in use. Also, the applicator can readily be moistened in this position without having the heating means vaporize the moisture absorbed and without having the moisture needlessly chill the heating means so that it is not as effective as desired when wall paper is to be removed. In Fig. 5, the parts are shown in their operative or wall paper removing position with the heating means 21 either pressing against and contacting the moisture applicator 25 or being in close proximity therewith. The springs 42 are easily overcome when the user exerts pressure on the handle 22 to press the moisture applicator firmly against the wall paper to be removed. When the heating means moves into the position in Fig. 5, it vaporizes the moisture in the applicator 25 and causes the hot vapors to permeate the wall paper to loosen the glue. The applicator 25 is firmly sandwiched between the heating means 21 and the wall paper 26 so that steam is only generated in a localized area, the steam being confined by the carrier means 30 and the heating means 21, and any pressure created while generating the steam will cause it to be driven through the wall paper 26.

Wetting or moistening of the applicator 25 must be strictly controlled. If it becomes too wet, it will drip down onto the floor and woodwork as it is carried over to the wall paper removing position in Fig. 5. If it is not wet enough, it will have to be moistened too frequently. Also, when the applicator 25 is moistened by being placed in contact with water or other satisfactory liquid, the heating means 21 must be kept away from the liquid to prevent chilling of the heating means and prevent the generation of needless steam. A moistening means, generally shown at 45, has been provided for wetting the applicator 25 in a controlled manner. This means engages the applicator 25 while it is spaced from the heating means 21. In Fig. 1, the applicator 25 and the heating means 21 are spaced apart in their inoperative position and the applicator 25 is spaced slightly above the moistening means 45. When the applicator 25 engages and is supported by the moistening means 45, the heating means 21 will still be in substantially the same spaced relationship due to the force exerted by the springs 42.

The moistening means consists of a pan 46 (Fig. 2) for retaining a pool of liquid and a liquid transfer means 47 in the pan contacting the pool and having an upper surface spaced from the pool for supporting the moisture applicator 25 and for transferring the liquid from the pool to the applicator. In the present disclosure, this takes the form of an absorbent pad or sponge, either a synthetic or natural sponge. This sponge will transfer the liquid from the bottom of the pan up to the applicator 25. It should be noted that the sponge 47 is smaller in width and length than the frame-like, applicator engaging portion of the carrier means 30 but is larger than the heating means 21. Hence, sufficient moisture is provided for full utilization of the heating means for generating steam but the cloth 25 is not needlessly saturated with liquid or moistened at its outer edges. There will be no danger of having liquid drip off of the applicator 25 as the unit is carried over into contact with the wall paper to be removed.

The top surface of the sponge 47 can either be flat or slightly convex upwardly. The latter structure is shown in Figs. 1 and 2 and provides a better contact 75 between the sponge and the applicator during wetting

since the full weight of the steam generating unit urges the applicator and sponge more tightly together.

The pan 46 has inwardly directed flanges 48, one on each of the four pan sides, above the liquid pool and each engaging one of the four sides of the sponge for retaining the sponge in the pan. These flanges 48 form a shelf for supporting the carrier 30 above the liquid pool when the applicator 25 is being moistened by the sponge 47. The upper surface of the sponge 47 will be depressed to a position approximately level with the top of the flange or ledge 48 under the weight of the steam generating unit. Fig. 9, illustrating another type of wall paper remover and being described in more detail later in the specification, illustrates the use of the flange 48.

The inwardly directed flanges 48, completely surrounding the sides of the sponge 47, can either be soldered or otherwise secured in the pan 46 or can be removably secured therein by the inclined side walls of the pan 46. The four flanges can be of frame shape as a continuous flange. Also, the inner edge of each flange can dig into the sides of sponge 47 and be removable therewith from pan 46. This invention also contemplates the structure wherein no sponge 47 is provided but pan 46 has the frame-like inwardly directed flange 48 in the position shown. The frame-like flange 48 will support the carrier 30 above the liquid pool and if there is a slight sag in the cloth applicator 25 it may contact the surface of the pool for wetting. The pool can be kept at a constant depth by having liquid supplied to the pool in response to the depth therein by any conventional type of control means. However, with this structure there is always the danger that the cloth applicator 25 will become too wet and will drip while being carried to the wall paper removing position.

Figs. 6 to 8 inclusive portray a modified form of wall paper remover. This device is exactly the same as that shown in Figs. 1 to 5 inclusive except for the construction of the carrier means 130. The carrier means in Figs. 6 to 8 inclusive includes a back wall 131 having forwardly or downwardly directed side walls or flanges 132 on all sides. A bead 133 is formed at the lower end of each side wall 132. This structure forms the main carrier means connected to the heating means 21 by the springs 42 and being provided with apertures 131a around the handle posts 23.

An auxiliary carrier means is also provided for supporting the cloth 25 and is detachably carried by the main carrier means. This auxiliary carrier means includes a frame 134 having upwardly or rearwardly bent outer edges 135. A resilient lug 136, adapted to snap over the bead 133 to secure the two components together, may be either welded or otherwise secured to the frame 134 at its lower edge or integrally formed from the frame 134 and bent into the shape shown in Fig. 7. Spaced lugs 136 are provided around the frame 134. For convenience and in no sense of limitation the lug 136 and the bead 133 are provided as a detachable connection between the carrier means and the auxiliary carrier means. However, any type of detachable connection could be used.

A modified form of toweling 125 may be detachably connected in another manner to bead 133, as shown in Fig. 7a. For example, the toweling 125 may have a drawstring 125b extending through loop 125a formed around the entire top of the toweling. Then, the ends of the drawstring can be tied with the drawstring forming a closed loop above bead 133 in Figs. 6 and 7 but with the toweling 125 extending below the heating means, as shown in the same figures.

However, the lug 136 has another function. The cloth 25 is detachably connected with the frame 135 and this detachable connection means may take various forms. Serrations may be provided on the upper edge of flanges 135, if desired. Also, the edge of the cloth 25 may

be pinched between the resilient lug 136 and the interface of the flange 135, if desired.

The frame 134 of the auxiliary carrier means has a handle 137 secured to one edge. It is useful during the assembly and disassembly of the two carrier means after they have been heated by the heating means 21 and the transporting of the applicator 25 when it is in its moistened or damp condition. Also, the handle 137 makes it possible to use the moisture applicator 25 with any other type of heating means desired in addition to the heating means 21.

Another form of wall paper remover is shown in Figs. 9 to 12 inclusive. The structure here is the same as that shown in Figs. 1 to 5 except for the specific changes mentioned hereinafter in the carrier means and the resilient connecting means between the carrier means and the heating means. In the structures in Figs. 1 to 8 inclusive, the carrier means 30 was formed separately from the resilient connecting means, the latter including spring 42 in Fig. 2. In Figs. 9 to 12 inclusive, these two means are substituted by an integral member 230 which performs both functions. It includes a spring member 240 adapted to engage the rear of the heating means 21 (Fig. 9) and having forwardly directed flanges at its opposite ends (Fig. 12). These forwardly directed spaced flanges 232, 232 are each greater in length than the thickness of the heating means 21. Spaced rivets 238, 238 secure the member 240 to the back or top surface of the heating means along the midpoint between the spaced flanges 232, 232. An elongated aperture 231a (Fig. 10) is located in the member 240 for the projection therethrough of the posts 23, 23 of the handle 22. The applicator 25 is secured to the distal or forward end of each of the flanges 232 by any suitable detachable connection, such as the serrated edges previously mentioned on members 33 and shown here in a similar manner on members 233.

The integral member 230 has a cloth applicator 25 stretched across its forward or lower distal edges. The springiness in the member 230 not only stretches the cloth 25 approximately flat in its lengthwise direction, if desired, but also serves as a resilient means to normally bias the applicator 25 and the heating means 21 into a spaced apart, inoperative position, as shown in Fig. 9. The resiliency is easily overcome by firmly pushing the handle 22 (Fig. 12) forward until the heating means 21 comes into contact with or in close proximity with the cloth applicator 25. Then, the parts are in their operative wall paper removing position. The applicator 25 is moistened by the wetting means 45 (Fig. 9) in the same manner as fully described heretofore. It should now be apparent that the integral member 230 performs the function of both the carrier means and the resilient connection between the carrier means and the heating means 21 and retains most of the superior features mentioned in describing Figs. 1 to 5 inclusive.

The operation of the present invention should now be apparent. Considering the wall paper remover of Figs. 9 to 12 inclusive, the moisture applicator 25 gets a controlled amount of water by being held in contact with the sponge 47 of the moistening means 45 in Fig. 9. The resiliency of the member 230 is sufficient to keep the moisture applicator 25 spaced from the heating means 21 during wetting while still permitting the parts to assume the position in Fig. 12 when the wall paper is to be removed. The user merely grasps the handle 22 and pushes the heating means toward the wall paper 26 so that the moisture in the applicator 25 will be changed to steam by the heat, driven under pressure through the wall paper 26 to soften the wall paper paste or glue. Then, the user utilizes a conventional scraper to remove the wall paper 26 from the wall.

The various forms of wall paper remover as disclosed in the present application have many advantages. Each is reasonable in price to manufacture, light in weight, and easy to use. The cloth applicator 25 can easily be

replaced on the carrier member even though the heating means 21 may be hot. The live steam penetrating the wall paper 26 is very hot since the steam is generated close to the wall paper surface and need not be conveyed thereto with the consequent loss of heat. This hot, live steam, hotter than that generated by the conventional wall paper steamer, will easily penetrate wall paper having a painted outer surface. This type of wall paper is generally very difficult to remove because the steam does not easily penetrate the surface coating. Steam is only generated when needed. No steam is generated when the parts are in their normal position as shown in Fig. 9. The high temperature of the steam enables the user to remove the wall paper faster and in greatest quantities for a given amount of steam released into the room.

The controlled wettings of the applicator 25 by the wetting means 45 have many advantages. The cloth applicator will not become soaking wet so that water will drip therefrom on the woodwork and floors as the steam generating means is moved from the position in Fig. 9 to that in Fig. 12. The steam generating unit is light in weight since a large water supply need not be carried with it as it is moved over the wall surface having the wall paper to be removed.

The wall paper removers, as disclosed in the present application, overcome many of the disadvantages found in prior devices. Each wall paper remover disclosed herein is much cheaper to construct and manufacture. There is no danger of blow-up by a steam boiler generating excessive pressure and no danger of an explosion by the burner for heating the boiler. No excess steam is generated to spoil the woodwork and other finished surfaces in the room or to make the room hot, humid and unbearable to work in. When the wall paper is attached to plastered walls, the plaster has a longer life since it is not subjected to a large amount of steam which would normally cause rapid deterioration.

Various changes in details and arrangement of parts can be made by one skilled in the art without departing from the spirit of this invention or the scope of the appended claims.

What I claim is:

1. A wall paper remover comprising a heating means, a moisture applicator, an applicator carrier means, and resilient means normally biasing said heating means and said applicator into inoperative position in spaced relationship with each other but easily overcome by pressure exerted on said heating means for urging it toward said applicator into operative position with said applicator sandwiched between said heating means and the wall paper to be removed, said resilient means and carrier means comprising a spring member adapted to engage the rear of said heating means and having forwardly directed flanges at opposite ends, each of said flanges being greater in length than the thickness of said heating means, said moisture applicator taking the form of a length of cloth secured to the forward distal ends of said flanges, the mid-point of said spring member between said flanges being secured to the back of said heating means.

2. A wall paper remover comprising a heating means; a moisture applicator; an applicator carrier means; resilient means normally biasing said heating means and said applicator into inoperative position in spaced relationship with each other but easily overcome by pressure exerted on said heating means for urging it toward said applicator into operative position with said applicator sandwiched between said heating means and the wall paper to be removed, said resilient means and carrier means comprising a spring member adapted to engage the rear of said heating means and having forwardly directed flanges at opposite ends, each of said flanges being greater in length than the thickness of

said heating means, said moisture applicator taking the form of a length of cloth secured to the forward distal ends of said flanges, the mid-point of said spring member between said flanges being secured to the back of said heating means, said spring member having an aperture between said flanges; and a handle secured to the rear of said heating means and extending rearwardly through said aperture.

3. A wall paper remover comprising a heating means, 10 a moisture applicator associated with said heating means for relative movement between a contacting and a non-contacting position, and a moistening means for engaging said applicator in said non-contacting position so that said applicator can absorb moisture without having it vaporize, said moistening means including a pan for retaining a pool of liquid and including a liquid transferring means in said pan contacting said pool and having a surface spaced from said pool for supporting said moisture applicator in said non-contacting position and for transferring liquid thereto from said pool.

4. A wall paper remover comprising a heating means, 15 a moisture applicator associated with said heating means for relative movement between a contacting and a non-contacting position, and a moistening means for engaging

20 said applicator in said non-contacting position so that said applicator can absorb moisture without having it vaporize,

25 said moistening means including a pan for retaining a pool of liquid and inwardly directed supporting flanges above said pool for supporting said heating means above said

30 pool in said non-contacting position while permitting said applicator to absorb moisture from said pool.

5. A wall paper remover comprising a heating means, 35 a moisture applicator associated with said heating means for relative movement between a contacting and a non-

35 contacting position, and a moistening means for engaging said applicator in said non-contacting position so that said applicator can absorb moisture without having it vaporize, said moistening means including a pan for retaining a pool of liquid and including a liquid transferring means in said

40 pan contacting said pool and having a surface spaced from said pool for supporting said moisture applicator in said non-contacting position and for transferring liquid thereto from said pool, said transferring means being a sponge.

6. A wall paper remover comprising a heating means, 45 a moisture applicator associated with said heating means for relative movement between a contacting and a non-contacting position, and a moistening for engaging said applicator in said non-contacting position so that said

50 applicator can absorb moisture without having it vaporize, said moistening means including a pan for retaining a pool of liquid and including a liquid transferring means in said pan contacting said pool and having a surface spaced from said pool for supporting said moisture applicator in said non-contacting position and for transferring liquid thereto from said pool, said transferring means being a sponge having an upwardly convex upper surface for making a good contact with said applicator.

7. A wall paper remover comprising a heating means, 60 a moisture applicator associated with said heating means for relative movement between a contacting and a non-contacting position, and a moistening means for engaging said applicator in said non-contacting position so that said applicator can absorb moisture without having it

65 vaporize, said moistening means including a pan for retaining a pool of liquid and including a liquid transferring means in said pan contacting said pool and having a surface spaced from said pool for supporting said moisture applicator in said non-contacting position and for trans-

70 ferring liquid thereto from said pool, said transferring means being a sponge, said moistening means also including inwardly directed flanges engaging the sides of said pan and said sponge above said pool for retaining said sponge in said pan and for supporting said heating means above said pool in said non-contacting position while

permitting said applicator to absorb moisture from said pool through said sponge.
